United States Patent Office

Des. 185,094
Patented May 5, 1959

185,094

FEED MIXER

Vernon V. Nash, Hopkins, Minn., assignor to Superior
Separator Company, Hopkins, Minn., a corporation of
Delaware

Application March 19, 1958, Serial No. 50,102

Term of patent 14 years

(Cl. D55—1)

FIG. 1

FIG. 2

FIG. 3

FIG. 4

Fig. 1 is a perspective view of a feed mixer showing my new design;

Fig. 2 is a view in top plan;

Fig. 3 is a view in rear elevation; and

Fig. 4 is a view in side elevation as seen from the opposite side with respect to Fig. 1.

I claim:

The ornamental design for a feed mixer, as shown.
